(57) **CLAIM**

The ornamental design for a motorcycle wind and rain deflector, as shown and described.

DESCRIPTION

FIG. 1 is a perspective view of a motorcycle wind and rain deflector;

FIG. 2 is a front elevational view of the motorcycle wind and rain deflector;

FIG. 3 is a rear elevational view of the motorcycle wind and rain deflector;

FIG. 4 is a top plan view of the motorcycle wind and rain deflector;

FIG. 5 is a bottom plan view of the motorcycle wind and rain deflector;

FIG. 6 is a left side view of the motorcycle wind and rain deflector; and,

FIG. 7 is a right side view of the motorcycle wind and rain deflector.

The broken lines in FIGS. 1-7 are for environmental purposes and form no part of the claimed design.
